UNITED STATES PATENT OFFICE.

WILLIAM E. WIDDUP, OF SPARTANBURG, SOUTH CAROLINA, ASSIGNOR TO DRAPER COMPANY, OF HOPEDALE, MASSACHUSETTS, A CORPORATION OF MAINE.

WARPING-MACHINE.

1,160,349.

Specification of Letters Patent. Patented Nov. 16, 1915.

Application filed April 28, 1913. Serial No. 763,945.

To all whom it may concern:

Be it known that I, WILLIAM R. WIDDUP, a citizen of the United States, and residing at Spartanburg, county of Spartanburg,

5 State of South Carolina, have invented an Improvement in Warping-Machines, of which the following description, in connection with the accompanying drawings, is a specification, like letters on the drawings

10 representing like parts. The invention to be hereinafter described relates to warping machines, and more particularly to the measuring means or "warper clock" which initiates operation of stopping

15 mechanism when a desired length of warp or yarn has been wound upon the beam.

As well understood by those skilled in the art, the importance of providing a definite or predetermined length of yarn on the 20 warp beam to be subsequently employed in the loom, has dictated that warping machines be provided with means whereby when the requisite or desired length of yarn has been wound on the beam, that the machine be stopped. Various expedients have been devised to this end, and means have been provided, the parts of which can be so set that if undisturbed, the warping operation may be accurately carried into effect

25 and the machine stopped when the desired length of yarn has been wound. Disturbance of the parts of such devices is liable to occur, however, either through carelessness of operatives, unauthorized handling, 30 or from other causes, and in such cases the length of yarn wound upon the beam will vary from that desired, and the recorded length thereof may not be true or accurate. Indeed, under such disturbing influences the 35 stopping means may fail to be automatically actuated, or may be caused to act too soon, as will be readily understood.

With these considerations in view, the 40 aims and purposes of the present invention are to provide means whereby the operative relation of the parts of said devices may be insured and maintained during the operation of the warping machine, so that a definite and predetermined length of yarn may 45 always be wound upon the beam, all of which, however, will best be made clear from the following description and accompanying drawing of one form of means for carrying the invention into practical effect.

In the drawings, Figure 1 is an end elevation of a sufficient portion of a warping machine to make clear the association of the invention therewith; and Fig. 2 is a detail sectional view on line 2—2, Fig. 1.

The warping machine may be of any general type or character wherein stopping means are employed in connection with a measuring device or "warper clock" to bring the machine to rest when the desired length of yarn has been wound upon the beam. For convenience in exploiting the present invention and making clear its construction and mode of operation, the invention is herein illustrated as associated and combined with the stopping means and "warper clock" of the patent to Rhoades, No. 624,541, dated May 9, 1899, to which reference may be had, but it is to be understood that it is not confined to the particular stopping means and "warper clock" of that patent but may be employed and combined with various other types of such devices.

Referring to the drawing, the frame 1, warp beam 2, the guides and other devices acting on the warp threads 3 as they travel to the beam 2, the stopping mechanism part of which is illustrated as comprising the rocker arm 4, the latch 5 pivoted to the rocker arm 4 at 6 and having the toe, the vibrator 8 pivoted at 9 and having the pin 80 or stud 10 and the roll or stud 11, the finger 12 mounted to slide and tilt upon the rod 13, the stop 14 and head 15 for acting upon the vibrator 8, and the stopping devices acting through these parts to stop the machine, 85 may all be substantially and operate on the same principle as set forth fully in said patent.

The measuring device or "warper-clock" for measuring and indicating the length of 90 yarn wound upon the beam, may be of any usual or desired character, such, for instance, as shown and described in the said Rhoades patent, and in exploiting, this feature of the device, the "warper-clock" of that patent is illustrated in the drawings hereof.

Referring to said drawings, the upright shaft 16 may be driven from some going part of the machine, as in said Rhoades patent, and carries a worm 17 for driving the 105 "warper-clock" through the worm 18 connected thereto. Connected to rotate in unison with the worm 18 is the spirally-grooved

shaft 19, which may take the form of a worm, as indicated in Figs. 1 and 2.

The spirally-grooved shaft 19 or worm, as it may be termed, is provided near a terminal portion of the spiral with a slot or recess 20, Fig. 1.

When the machine is to be started to effect the warping operation, the finger 12 is applied to the worm or spirally-grooved shaft 19, and as the said shaft 19 is slowly rotated through the means hereinbefore indicated, the finger 12 travels along its shaft 13 until the end thereof drops into the recess 20 of the worm, whereupon the head 15 of

the stop drops in front or to the left of the stud or roll 11 on the vibrator arm, whereupon the machine will be brought to rest as fully set forth in the Rhoades patent hereinbefore called to attention.

Obviously the finger 12 is liable to become disengaged from the worm or spirally-grooved shaft 19, and to obviate this there is provided a weighted arm 21 depending from a sleeve 22 on a stud or shaft 23, Fig. 2, and said sleeve 22 has extending therefrom a bearing piece 24 which, under the action of the weighted arm 21, is caused to maintain itself in contact with the finger 12 and hold the same in operative relation with the worm 19 as the finger is moved longitudinally of its support 13 by the said worm.

It will happen at times, through carelessness of the operative, or through unauthorized handling, or it may be through the vibrations of the machine itself, that the sleeve 22 carrying the weighted arm 21 may be turned upon its supporting stud or shaft 23 and permit the bearing piece to become disengaged from the finger 12, so that the said finger may fail to travel continuously on its support 13 as the worm 19 is rotated. This interruption of the travel of the finger may be only temporary, or it may be disengaged altogether from the worm 19, but in any event, it will be evident that since the warp beam is continued in its rotative movement to wind the yarn thereon, and the clock is itself being rotated, a true record of the length of yarn placed upon the beam will not be furnished by the clock. The stopping mechanism under these conditions may be caused to act either prematurely or too late. Thus the length of yarn upon the beam becomes indeterminate, and if this be not detected it will be put in the loom, and result in considerable loss. One of the purposes of the present invention, therefore, is to overcome this liability of the finger being disengaged from its operating means, such as the worm 19, and to insure that when the warping machine is started to wind the warp or yarn upon the beam, that it as well as the clock or measuring means will continue in operation until the beam has been properly wound, whereupon a predetermined amount

of yarn will have been placed upon the beam and the clock may be provided with means to indicate the amount.

As one simple means to the ends noted, the sleeve 22 and stud or shaft 23 are provided with mutually co-acting means to maintain the bearing piece 24 in operative relation with the finger 12 as the latter moves throughout its range of travel. In other words, means are provided so that when the finger 12 has been placed in engagement with the worm 19 and the bearing piece 24 has been placed in operative relation thereto so that the finger 12 cannot be disengaged from the worm, the means contemplated by the invention locks the bearing piece 24 in said position and maintains it in such position during the entire traveling movement of the finger 12, the result being that neither through the jar of the machine nor through carelessness of the operative or unauthorized handling can the operative relation of the clock and its finger co-operating devices be disturbed, so that the required and desired length of yarn will always be placed upon the beam.

A simple form of means to the above ends consists in providing the sleeve 22 and stud or shaft 23 each with an opening or slot so that when the bearing piece 24 is in operative relation with the finger 12, such openings or slots are properly related to receive a locking device, such as a pin or stud 25, Fig. 2. This locking stud or pin 25 may be conveniently formed as indicated by Fig. 2, and be provided with a head 26 to rest upon the sleeve 22 when passed through the openings of said sleeve and stud or shaft, and to prevent withdrawal of said pin by unauthorized persons it is provided with an opening 27 through which may be passed the arm 28 of a lock 29. This lock 29 may be conveniently formed as a padlock of ordinary construction, so that when engaged with the opening 27 of the locking pin 25 and properly secured, it will be impossible for anyone unprovided with a key to disturb the operative relation of the clock and bearing finger 12.

In operation, the finger 12 will be moved opposite a part of the worm 19 appropriate to the length of yarn to be placed upon the beam, and will then be engaged with said worm. The bearing piece 24 will then be placed in position as indicated by Figs. 1 and 2 and then the locking pin 25 will secure the sleeve 22 and bearing piece in the assumed position. When the beam has been fully wound and the machine has been stopped through the instrumentalities hereinbefore described, the person carrying the key to the lock 29 may manipulate the same to permit withdrawal of the locking pin 25, whereupon the parts may be reset for another winding of the yarn upon a beam.

While the locking pin 25 and the lock 29 constitute simple and effective means for the purposes hereinbefore noted, it is to be understood that other devices which will serve to lock or maintain the bearing piece 24 in operative relation with the finger 12 so that the latter shall maintain its coöperative relation with the "warper-clock" during the entire wind of the beam, may be employed within the true scope of the actual invention.

What is claimed is:—

In a warping machine, the combination of stopping means, warp measuring mechanism, devices intermediate the warp measuring mechanism and stopping means to cause operation of the stopping means when a pre-

determined length of yarn has been wound upon the beam, means for preventing disengagement of said intermediate devices and measuring means during the winding operation, and means for locking said last mentioned means in operative position, whereby the actual length of yarn wound on the beam will be the same as that indicated by the measuring device.

In testimony whereof, I have signed my name to this specification, in the presence of two subscribing witnesses.

WILLIAM R. WIDDUP.
